REVERSIBLE FEED MECHANISM FOR
SEWING MACHINESJames Heggie, Clydebank, Scotland, assignor to
The Singer Manufacturing Company, Elizabeth,
N. J., a corporation of New JerseyApplication March 7, 1946, Serial No. 652,711
In Great Britain March 24, 1945

4 Claims. (Cl. 112—210)

1

This invention relates to improvements in reversible feed mechanism for sewing machines.

The invention is concerned with four motion feed mechanism of the type including a work-engaging feed dog having operative connections with a feed advance rock shaft and with a feed lift rock shaft which are located below the machine bed-plate and to which rocking movements are communicated.

Reversible feed mechanism according to the invention includes a normally stationary guide block angularly adjustable about an axis parallel to said rock shafts, said block presenting a curved slot, an arm operatively connected to the feed advance rock shaft, a follower on said arm, said follower engaging said slot, and means for effecting angular adjustment of said guide block whereby to cause reversal of the direction of feed.

In the accompanying drawings Fig. 1 is a view of the underside of the bed-plate of a sewing machine embodying reversible feed mechanism according to the invention; Fig. 2 is a vertical sectional view through the machine bed-plate and partly through the standard of the sewing machine bracket arm, looking from the head end towards the driving end of the machine, the section being mainly on the line II—II of Fig. 1, and the movable parts of the mechanism being shown as for forward feeding movement; Fig. 3 is a fragmentary head end view showing the conventional four-motion mechanism; Fig. 4 is a view similar to Fig. 2, but showing certain of the parts in a different position of operation; Figs. 5 and 6 are similar views to Figs. 2 and 4, respectively, but showing the mechanism disposed as for reverse feeding movement. Fig. 7 is a perspective view of parts of the feed advance mechanism, hereinafter to be described.

Referring to the drawings, 1 denotes the standard of the usual bracket arm uprising from the bed-plate 2 of a conventional type of lock-stitch sewing machine having an upper rotary needle-actuating shaft 3 and a lower rotary loop-taker shaft 4 carrying a loop-taker 4'.

The work-feeding mechanism includes a work-engaging feed dog 5 carried by the usual feed-bar 7, which is pivotally connected at 8 to an upstanding arm 9 secured on a feed advance rock shaft 10 journaled below the bed-plate 2, and which is provided at its opposite end with a slot 11 engaged by a slide block 12 on an arm 13 secured on a feed-lift rock shaft 14. The rock shafts 10, 14 are given their rocking movements by pitmans 15, 16 operated, for example, from eccentrics, as 17, on the upper shaft 3. The lower

2

end of the pitman 15 is pivotally connected to an arm 17' of a U-shaped follower 17 which in turn is pivotally connected at 17' between two radial arms 18 provided by a member 18a secured on the shaft 10. (See Fig. 1.) The lower end of the pitman 16 is pivotally connected to an arm 20 secured on the rock shaft 14.

Referring now to the feed reversing means of the machine, 21 denotes a normally stationary 10 slotted guide block member presenting an arcuate slot 22 and carried by a short shaft 23 journaled beneath the bed-plate 2 in parallelism with the rock shafts 10, 14. The construction is such that the guide block member 21 may be adjusted angularly about the axis of the shaft 23 by means operable from above the bed-plate 2, so as to effect reversal of the direction of feed.

The slot 22 in the guide block member 21 is engaged by a follower stud or roller 24 on the free 20 end of a relatively long arm 25 forming part of the follower 17.

In the normal actuation of the machine the setting of the guide block member 21 is such that the axis of curvature of the slot 22 in the member 25 is almost coincident with the axis of the feed advance rock shaft 10. Under these conditions the forward feed motion is obtained.

When it is desired to effect reversal of the direction of feed, the guide block member 21 is turned through a predetermined angle into "reverse" setting as shown in Figs. 5 and 6 in which its axis of curvature is located considerably above the axis of the feed advance rock shaft 10. As a result of this adjustment of the guide block member 21 reversal of the direction of feed is obtained, the follower roller 24 being constrained by the slot 22 to impart reverse feed movement to the feed advance rock shaft 10.

For effecting adjustment of the guide block member 21 there is provided a plunger 26 guided in an aperture in the bed-plate 2 and adapted to be depressed manually against spring action in order to effect reversal of the direction of feed. The lower end of the plunger 26 is pivotally connected to the mid or free pivot 27 of a pair of toggle levers 28, 29 one 28 of which is pivotally connected at 30 to the guide block member 21 and the other 29 of which has a stationary pivot 31 carried by a member 31a rigidly connected with the bed-plate 2. The toggle lever 29 is influenced by a spring 32 which tends to retain the toggle levers 28, 29 in straightened condition, i. e., in the position in which the guide block member 21 is set in normal or forward feed position. When the toggle 50 gle is broken by depression of the plunger 26, the

guide block member 21 is set in "reverse" feed position. When the plunger 26 is freed the feed mechanism is restored to forward feed position by the action of the spring 32. If desired, a manually operable detent may be provided for engagement with the plunger 26 to hold the mechanism in "reverse" position.

Stops 33, 34 and an adjustable stop 35 are provided to limit the range of travel of the toggle levers 28, 29 and of the guide block member 21.

In the present construction the plunger projects through the bed-plate for convenient access. It may, however, be found convenient to arrange the plunger to project to the front of the machine below the bed-plate.

It is to be understood that while the drawings show an upper shaft connected by pitmans with the feed advance rock shaft and the feed lift rock shaft, these rock shafts may derive their rocking movements from a shaft located beneath the bed-plate.

As illustrated in the drawings, the feeding mechanism is given its maximum movements in forward and reverse directions. It is to be understood, however, that the length of the feeding stroke is dependent upon the length of endwise reciprocation given to the pitman 15 by its actuating eccentric. In machines wherein it is desired to vary the length of the feed, as well as to reverse its direction, any conventional or preferred form of adjustable eccentric device may be employed to variably reciprocate the pitman 15.

What I claim is:

1. In a sewing machine having a bed-plate; work-feeding mechanism below said bed-plate including a feed-dog, a feed advance rock shaft and a feed lift rock shaft, connections between said shafts and said feed dog for imparting a four-motion movement to said feed dog, means including an oscillatory actuating arm, having an axis of oscillation located above and connected with the feed advance rock shaft, for communicating rocking movements to said feed advance rock shaft, means for communicating rocking movement to said feed lift rock shaft, a normally stationary guide block located beneath said bed-plate and angularly adjustable about an axis parallel to said rock shafts, said block presenting a curved slot of which the axis of curvature is normally eccentric to the axis of oscillation of said arm, a follower roller on said arm, said follower roller engaging said slot, and means for effecting angular adjustment of said block about its axis to effect reversal of the direction of feed.

2. In a sewing machine, work-feeding mechanism as claimed in claim 1 in which the means for effecting angular adjustment of the guide block includes a spring-biased toggle lever device having one end pivoted to a member rigidly connected with the bed-plate and its other end pivotally connected to said block, said toggle lever

device being adapted to be "broken" against spring action, thereby to change the angular position of said block, when it is desired to effect reversal of the direction of feed.

3. In a sewing machine, work-feeding mechanism as claimed in claim 1 in which the means for effecting angular adjustment of the guide block includes a spring-biased toggle lever device having one end pivoted to a member rigidly connected with the bed-plate and its other end pivotally connected with said block, said toggle lever device being adapted to be "broken" against spring action, thereby to change the angular position of said block, when it is desired to effect reversal of the direction of feed, and in which the means for "breaking" the toggle lever device comprises a manually operable member having its lower end pivotally connected to said toggle lever device and its upper end projecting upwardly through said bed-plate for engagement by the machine operator.

4. In a sewing machine having a frame, including a bed-plate and an overhanging bracket-arm, and a rotary shaft journaled lengthwise of said bracket-arm; a work-feeding mechanism comprising a horizontally disposed feed-bar located beneath said bed-plate and carrying a feed-dog, means to elevate and depress said feed-bar, means to reciprocate said feed-bar including an eccentric on said shaft, a feed advance rock shaft journaled beneath said bed-plate, an arm on said feed advance rock shaft operatively connected to said feed-bar, a member secured on said rock shaft and having two radial arms, a U-shaped follower pivotally mounted between said radial arms and having a pair of arms of unequal length, an upright pitman having its upper end surrounding said eccentric and its lower end pivotally connected to the shorter arm of said U-shaped follower to oscillate said follower, a normally stationary guide block located beneath said bed-plate and angularly adjustable about an axis parallel to said rock shaft, said block being provided with a slot having curved walls, a roller carried by the free end of the longer arm of said follower and located between the walls of said slot, said walls normally being at an angle to an arc swung from the pivotal axis of said U-shaped member and acting on said roller to effect oscillatory movements of said feed advance rock shaft, and means for effecting angular adjustment of said block about its axis to effect reversal of the direction of feed.
